TEETER-TOTTER

Paul Buczkowski, Detroit, Mich.

Application February 15, 1946, Serial No. 647,835

4 Claims. (Cl. 272—54)

1

This invention relates to teeter-totters and in particular to teeter-totters of a collapsible type. The primary object of the invention is to provide an improved teeter-totter characterized by its simplicity, which is economical to manufacture, which may be easily collapsed and stored away in a small space or transported in an automobile, which may be readily erected for use, which may be used indoors as well as out-of-doors without skidding over smooth floors or sinking into soft ground, which may be conveniently adapted for use by children of unequal weight, and which has a novel arrangement of parts and construction that provides unusual strength and ruggedness for its extremely light weight.

Other objects of the invention will become apparent by reference to the following detailed description taken in connection with the accompanying drawing, in which:

Fig. 1 is a side elevational view of a teeter-totter embodying the invention with portions thereof broken away to illustrate the construction.

Fig. 2 is a plan view of the teeter-totter disclosed in Fig. 1.

Fig. 3 is a fragmentary exploded view showing how the teeter-totter is readily collapsed when not in use.

Fig. 4 is an elevational view taken on the line 4—4 of Fig. 3 showing the base member further collapsed for convenient storage.

Fig. 5 is an enlarged sectional view taken on the line 5—5 of Fig. 3 showing an end view of the central bridge member.

Referring now to the drawing wherein like numerals refer to like and corresponding parts throughout the several views, the teeter-totter disclosed for the purpose of illustrating the invention comprises a base 10 including a fulcrum member 11, a rocking beam generally designated by the numeral 12 including a bridge assembly 13 and a pair of beam members 14 joined together as hereinafter described. Each beam member 14 is composed of a main element 31 and auxiliary element 32 hereinafter more fully described in detail. A seat 15 is positioned at the outer end of each main element 31 and a handle bar 16 is secured on the outer end of the auxiliary element 32. As hereinafter more fully described in detail, the said auxiliary element 32 of each beam member 14 is so shaped and fixed in cooperating engagement with the main element thereof and the said beam members 14 are so assembled in cooperating engagement with each other through the bridge assembly 13 as to provide a rocking

2

beam 12 of great strength and rigidity, all accomplished while employing the minimum of means for securing the teeter-totter in assembled relationship from its collapsed state ready for storage, shipment or transport in an automobile.

The base 10 is composed of a fulcrum member 11 having a sleeve 18 welded on each end thereof disposed normal with respect thereto. 10 Through each of the said sleeves 18 an inverted U-shaped fulcrum supporting member 19 is telescoped with the horizontal portion thereof in turnable relationship with respect to the said sleeve 18. A bolt 20 disposed vertically through 15 each sleeve 18 and fulcrum supporting member 19 fixes the said fulcrum and fulcrum supporting members in the desired assembled relationship as indicated in Figs. 1, 2 and 3. By removing the bolts 20 and turning the fulcrum supporting members 19 in the sleeves 18 as indicated by the dotted lines 21 and 22 in Fig. 4 from the position indicated by the dot and dash lines to the position indicated by the full lines therein, the said base 10 may be collapsed to the compact folded position as indicated in full lines in Fig. 4. The lower ends of the said inverted U-shaped fulcrum supporting members 19 are each provided with a flange 23 and a preferably resilient rubber foot 24. The flange 23 is employed to prevent the base 10 from sinking into soft ground when the teeter-totter is used out-of-doors and the resilient rubber foot prevents damage to finished floors when the teeter-totter is used indoors.

The bridge assembly 13 is composed of a pair of spaced abutments 25 preferably formed to provide a plurality of unequally spaced arches 26 concaved to rest on the fulcrum member 11 as shown in Figs. 1 and 2. The said abutments 25 are held in the desired spaced relationship by 35 bridge beams 27 preferably welded to the top of the outer arches 26 of the abutments 25. By spacing the outer pair of arches 26 on each side of the center pair of arches 26 at different distances therefrom, the balance of the rocking beam 12 may be altered by shifting the same so that either one or the other of the outer pair of arches 26 rests on the fulcrum member 11. Thus the teeter-totter becomes usable by children of unequal weights. A compression splice sleeve 28 is supported on and is welded to the top of the bridge beams 27 midway between and parallel to the spaced abutments 25 of the bridge assembly 13, see Figs. 2 and 5. A tension splice rod 29 is supported in spaced relationship directly above and parallel to the said compression

splice sleeve 28 on a pair of diagonally disposed struts 30 welded at their upper end to the longitudinal center of the said tension splice rod 29 and at their lower end to the longitudinal center of the top of the center arch 26 of the bridge assembly 13, see Figs. 2 and 5. The construction of the beam members 14 of the rocking beam 12 is so arranged as hereinafter described to avoid any stress from the splice thereof to be taken by or transferred to the struts 30. The struts 30 merely maintain the rocking beam 12 in its vertical position after the beam members 14 are assembled in spliced relationship on the bridge assembly 13 to form the said rocking beam 12.

Each beam member 14 comprises a lower preferably tubular main element 31 and an upper preferably tubular auxiliary element 32 disposed parallel to and in vertical spaced relationship above the main element 31 at the inner end thereof and separated therefrom near the inner end thereof by a vertically disposed strut 33 welded to the top of the main element 31 and the bottom of the auxiliary element 32. The said auxiliary element 32 is bent downwardly from its inner end as indicated in Fig. 1 to converge with the main element 31 at approximately the outer third point thereof and then upwardly and outwardly to form a support for the transversely disposed handle bar 16 welded to the outer end of the said auxiliary element 32. The said auxiliary element 32 is securely welded to the top of the main element 31 at the point of convergence therewith. A saddle type seat 15 preferably formed from metal is welded onto the top and outer end of the main element 31 by welds 34 and 35. Hand grips 36 are preferably telescoped over the ends of the handle bar 16.

The upper element 32 of each beam member 14 is provided with a vertical aperture therethrough near the inner end thereof to register with vertical apertures provided through the tension splice rod 29 near its supporting struts 30 to accommodate bolts 37 which are employed to accomplish a tension splice between the auxiliary elements 32 of oppositely disposed beam members 14 through the tension splice rod 29 of the bridge assembly 13 after the said beam members are assembled in telescopic relationship with respect to the said bridge assembly 13 as indicated in Figs. 1 and 2. It will be noted that when so assembled, the main elements 31 of the beam members 14 are telescoped into abutting relationship with respect to each other within the compression splice sleeve 28 of the bridge assembly 13 to accomplish a compression splice as indicated by the dotted line 38 in Fig. 1 while the auxiliary elements 32 of the beam members 14 are telescoped over and anchored to the tension splice rod 29 of the said bridge assembly 13 by the bolts 37 as hereinbefore described. This construction not only permits the disassembly of the rocking beams 12 into three convenient parts but provides a very light yet extremely strong teeter-totter rocking beam easy to erect and economical to manufacture.

Although but one embodiment of the invention has been disclosed and described in detail, it is obvious that many changes may be made in the size, shape, arrangement and detail of the various elements thereof without departing from the spirit of the invention as defined by the appended claims.

I claim:

1. In a teeter-totter comprising a base including a fulcrum member and a rocking member,

said rocking member consisting of a bridge assembly and a pair of oppositely extending beam members, the said bridge assembly including abutments disposed in parallel lateral spaced relationship one on each side of said beam members, bridge beams spanning between said abutments, each of the said beam members comprising upper and lower portions means for supporting and compression splicing said lower portion of the said beam members carried by said bridge beams, means for tension splicing said upper portion of the said beam members, and struts for maintaining said beam members in a vertical position extending upwardly and inwardly from the said abutments carrying the said means for tension splicing said upper portions of the said beam members.

2. In a teeter-totter comprising a base including a fulcrum member and a rocking member, 20 said rocking member consisting of a bridge assembly and a pair of oppositely extending beam members, the said bridge assembly including abutments disposed in parallel lateral spaced relationship one on each side of said base members, bridge 25 beams spanning between said abutments, each of the said beam members comprising upper and lower portions means for supporting and compression splicing said lower portions of the said beam members carried by said bridge beams, 30 means for tension splicing said upper portions of the said beam members, and struts for maintaining said beam members in a vertical position extending upwardly and inwardly from the said abutments carrying said means for tension splicing 35 said upper portions of the beam members, each of said abutments being formed into a plurality of unevenly spaced opposite arches adapted to ride said fulcrum member in pairs whereby to accommodate the teeter-totter to use by children of unequal weight.

3. In a teeter-totter comprising a base including a fulcrum member and a rocking member, said rocking member comprising a bridge assembly including laterally spaced abutments adapted 45 to rock on said fulcrum carrying a compression splice sleeve, a tension splice member disposed in spaced relationship above said compression splice sleeve, and diagonally disposed struts extending upwardly and inwardly from said laterally spaced abutments supporting the said tension splice member, and a pair of oppositely extending beam members each composed of a lower main element, an upper auxiliary element and a vertically disposed strut member spacing said main 55 and auxiliary elements fixed to both the main and auxiliary elements from which vertically disposed strut member the said auxiliary element extends outwardly downward to the said main element where it is fixed thereto and from whence the said auxiliary element is extended further outwardly and upwardly, a handle bar transversely disposed on the outer upwardly extended end of the auxiliary element, the inner ends of the said main and auxiliary elements of each beam 60 member being telescoped into and over opposite ends of the said compression splice sleeve and tension splice member of the bridge assembly respectively with the opposite ends of the said main elements in abutment, and means for securing said auxiliary elements in said telescopic relationship to said tension splice member.

4. In a teeter-totter comprising a base including a fulcrum member and a pair of inverted U-shaped fulcrum supporting members, and a 75 rocking beam adapted to seesaw with respect to

said fulcrum, the said fulcrum member having a sleeve disposed horizontally normal thereto fixed on each end thereof through which the horizontal portion of an inverted U-shaped supporting member is telescoped in turnable relationship thereto whereby to permit the said U-shaped member to be rotated from an inverted U-position supporting said fulcrum member to a substantially horizontal position for storage, and means disposed through each sleeve and inverted U-shaped member for securing the said U-shaped supporting member in its inverted U-position with respect to the said fulcrum member, the said rocking member consisting of a bridge assembly and a pair of oppositely extending beam members, the said bridge assembly including abutments disposed in parallel lateral spaced relationship one on each side of said beam members, bridge beams spanning between said abutments, each of the said beam members comprising an upper and lower portion, means for supporting

and compression splicing said lower portion of the said beam members carried by said bridge beams, means for tension splicing said upper portion of the said beam members, and struts for maintaining said beam members in a vertical position extending upwardly and inwardly from the said abutments carrying the said upper portion of the means for tension splicing said beam members.
